HENRY BLANCHARD, OF ALLIANCE, OHIO, ASSIGNOR TO AMERICAN STEEL
FOUNDRIES, OF NEW YORK, N. Y., A CORPORATION OF NEW JERSEY.

CENTERING DEVICE FOR COUPLINGS.

1,105,611.

Specification of Letters Patent.

Patented Aug. 4, 1914.

Application filed September 19, 1912. Serial No. 721,213.

To all whom it may concern:

Be it known that I, HENRY BLANCHARD, a citizen of the United States, residing at Alliance, in the county of Summit and State 5 of Ohio, have invented certain new and useful Improvements in Centering Devices for Couplers, of which the following is a specification.

My invention relates to railway cars and 10 has particular reference to a novel car-coupler centering mechanism.

The principal object of the present invention is to provide a centering device for use in connection with passenger equipment.

15 On long passenger-cars, many railroads require that a centering device shall be provided, that is, an automatic centering mechanism by means of which the coupler is maintained in longitudinal alinement with 20 the car when the car is unattached to other cars. This centering mechanism also assists in straightening the couplers into longitudinal alinement when the cars are in service and after passing from a curve, it being 25 understood that while on the curve the couplers must deflect.

Generally stated, the mechanism described includes a coupler-head provided with a tail, draft-rigging mechanism; and a 30 stem or link connecting the draft-rigging mechanism to the coupler at a point near the coupler head. Spring cushions are provided on each side of the coupler-shank and connecting link. By my arrangement the 35 coupler is permitted the maximum angular movement and such angular movement is secured without affecting in any way the draft-rigging mechanism. Furthermore, the arrangement is such that under side-wise 40 movement of the coupler-head both spring cushions are brought into action, in distinction from devices in which only one spring cushion is caused to act at each deflection of the coupler-head. A point to be noted is 45 that the centering device is independent and self-contained and does not form an essential auxiliary part of the draft-rigging, neither is the coupler or shank in any way weakened by the presence of the centering 50 device, the parts being serviceable without the centering device.

Another feature is in the construction of 55 the cushioning devices in that they may be easily removed and inspected without interfering with the coupler or draft-rigging.

The invention will be more readily understood by reference to the accompanying drawings, wherein—

Figure 1 is an elevation partly in section showing my novel centering device, and 60 Fig. 2 is a plan view also partly in section.

Referring more particularly to the drawings, it will be seen that between suitable sills 10 are secured the face-plates 11 of draft-rigging mechanism. Springs, not 65 shown, are located as will be well understood. A yoke 12 surrounds the springs. A coupler 13 of any preferred form is provided with a bifurcated shank 14 extending rearwardly to a point close to the yoke 12. 70 A stem 15 is secured to the yoke 12 by means of the pivot-pin 16, connection to the coupler being at a point close to the coupler-head by means of a short pin 17. This pin is preferably flush with the top and bottom 75 surfaces of the shank 14, in order that the coupler may move forward and backward without restriction. The coupler is supported on a suitable carry-iron 18. It will be seen that the connection between the 80 draft-gear and the coupler is at a point close to the coupler-head and that the ends of the shank 14 are free to oscillate.

My novel cushioning devices are applied to the center sills 10, the face-plate 19 being 85 secured to the inner face of the sill, and a housing 20 to the outer face of the sills. A plunger 21 having an integral stem 22 is passed through the opening in the sills and fits snugly the housing 20 and the face-plate 90 19. The plunger is provided with long bearing surfaces 23, a spring 24 being seated between the shell 23 and the integral stem 22 bearing against the plunger and the end wall of the casing 20. The tension of the 95 spring 24 may be adjusted and the motion of the plunger limited by means of suitable nuts 25 secured to the stem 22. It will be seen that the plunger is sufficiently wide to bear against both the bifurcated ends of the 100 shank 14 and the stem 15. Furthermore, that in the extreme movement of the spring-pressed plunger, it is guided and the spring entirely inclosed. This prevents the possibility of the spring being broken by side 105 thrust or torsional strains, and, furthermore, the spring is entirely protected from the weather. In case a spring should be broken in service, such fact is clearly indicated by the position of the projecting-end 110

of the stem. In such case the casing 20 is removed, whereupon a new spring may be applied and the parts re-assembled in a very short time, it being entirely unnecessary to interfere with either the coupler or draft-rigging.

An advantage arising from the construction of the coupler shank and its connection to the draft-rigging is in that under side 10 movement of the coupler-head, both centering springs may be brought into action; that is, referring to Fig. 2, assuming a movement of the coupler-head in the direction of the arrow, the shank 14 will tend to press 15 the lower plunger 21 whereas the stem 15 will tend to compress the upper plunger 21. By this arrangement, much lighter springs may be used, in that both springs are brought into action at each deflection of the 20 coupler. Furthermore, by my novel mounting of the springs longer and more flexible springs may be installed.

Many other advantages accrue from the 25 employment of this construction and I am aware that modifications may be made in the exact form herein shown. Such modifications as are within the scope of my claim, I consider within the spirit of my invention. 30

I claim:

In a device of the class described, the combination of draft sills carrying draft rigging stops, a yoke, a stem pivoted to and projecting forwardly from said yoke, a bifurcated coupler shank, means for pivoting said stem to said shank at a point near the forward end of said shank, and centering springs carried by said sills and having a bearing on both said stem and said shank, 40 substantially as described.

HENRY BLANCHARD.
